UNITED STATES PATENT OFFICE.

GEORGE H. WEBB, OF PAWTUCKET, RHODE ISLAND.

FURNACE FOR HEATING BLANKS.

SPECIFICATION forming part of Letters Patent No. 291,967, dated January 15, 1884.

Application filed April 21, 1883. (No model.)

To all whom it may concern:

Be it known that I, GEORGE H. WEBB, of Pawtucket, in the county of Providence, in the State of Rhode Island, have invented a certain new and useful Improvement in Blast-Furnaces for Heating Bolt-Blanks; and I declare the following to be a specification thereof, reference being had to the accompanying drawings.

10 Like letters indicate like parts.

Figure 1 is a perspective view of my invention. Fig. 2 is a detail view. Fig. 3 is a vertical section on the line *x x* of Fig. 4. Fig. 4 is a front elevation of my invention.

15 My invention relates to blast-furnaces in general, but more especially to the piling-furnaces used in bolt-manufacture for the heating of the bolt-blanks.

The invention consists in the construction and arrangement of parts, as hereinafter more fully described and claimed.

The drawings represent my said invention as applied to a double rotating blast-furnace.

Upon the base A is erected the air-chamber B, which receives a blast of cold air through the pipe C. Said air-chamber is covered by a top piece, D, which revolves horizontally on the balls *a*, and supports the double blast-furnaces and their appurtenances.

20 Through a central aperture of the cover D is the pipe E, opening into the cross-pipe F, which conveys the blast through the wind-boxes G G', respectively, and through the ash-boxes H H' and beneath the grates I I' of the fire-boxes J J'. The blast may be cut off from either furnace, as desired, by means of the dampers K, operated by the handles L L and rods M M' M'' M''. Branch blast-pipes N N' open into the cross-pipe F, and convey the

25 air-blast to the wind-boxes O O'. A gate, P, is placed in each pipe N N', to shut off or regulate the air-currents in either pipe, as desired. Said wind-boxes O O', on each side, are placed in front of the boxes H H', just below the plane 30 of the grates I I'. A shelf, Q, extending in front of said fire-box J, fits over and covers the wind-box O, and has a central longitudinal slot, b, permitting the escape of the air upward. A metallic case, R, forms the exterior walls of the furnace, being suitably

lined, as shown in Figs. 2 and 3, and fits within the ledges *c c*. A dome, S, having a central funnel, covers the furnace. The bolt-blanks T are piled in the open space below the iron plate or fender U, upon the hearth V, as 55 fully shown in Fig. 3, and their heads are thus brought into direct contact with the mass of burning coal in the fire-box J. The fender U extends downward near to the hearth V, and is supported within the vertical grooves 60 of the bolt-guides W. The construction and arrangement of these parts are shown in horizontal section in Fig. 2, as seen on the line 1 2 of Fig. 4. The bolt-guides W have a sloping edge (see Fig. 4) to facilitate the feeding of 65 the bolts T. As the lowest bolts are withdrawn, as illustrated in Fig. 3, the bolts above fall or slide along the sloping edges of the bolt-guides to a central position, instead of piling in the corners, as they would do if they 70 dropped vertically into place. The bolt-guides W rest upon the shelf Q, and are held in position there by their own weight. They have vertical grooves d d on each side, and when the inner surface of said guides has been burned 75 out, they can be lifted out of position and turned around or reversed to bring the opposite side to the fire.

The blast in other furnaces drives out the flames and heat, and prevents the workman 80 from conveniently removing such heated blanks; but my device intercepts and diverts the hot-air currents by a strong vertical blast of cold air. The cold blast passes from the air-chamber B up through the pipes E, F, and 85 N into the wind-boxes O O', whence it escapes through the openings or slots b b, with force sufficient to cut off the horizontal hot-air currents issuing between the pile T from the fire-box, thus forming, as it were, a body or screen 90 of cold air in front of the furnace and shielding the workman from the intense heat, while permitting close handling of the heated blanks, as shown in Fig. 2.

I claim as a novel and useful invention and 95 desire to secure by Letters Patent—

1. In a piling-furnace, the combination of a fire-box, J, shelf Q, and the side bolt-guides, W, having inclined edges, substantially as described.

2. In a piling-furnace, the bolt-guides W, having vertical grooves d d , in combination with the fender U and shelf Q, substantially as described.
- 5 3. In a piling-furnace, the combination, with the air-chamber B, pipes E F F', fire-boxes J J', having grates II', the ash-boxes H H', wind-boxes G G' and O O', and connecting-pipes N N', having means for controlling a blast, of the shelf Q, side bolt-guides, W W, and fenders to U U, substantially as described.

GEORGE H. WEBB.
